(57) **CLAIM**

The ornamental design for a ring, as shown and described.

DESCRIPTION

FIG. 1 is a perspective view of a first embodiment of a ring in an assembled arrangement;

FIG. 2 is a front view of a ring in an assembled arrangement. The back view is a mirror of the front view.

FIG. 3 is a right side view of a ring in an assembled arrangement. The left side view is a mirror of the right view.

FIG. 4 is a top view of a ring in an assembled arrangement.

FIG. 5 is a bottom view of a ring in an assembled arrangement.

FIG. 6 is an exploded perspective view of a ring; and,

FIG. 7 is a perspective view of a second embodiment of a ring in an assembled arrangement.

The broken lines shown in the drawings represent portions of the ring which form no part of the claimed designed.
